Primary Examiner — Mark Booker(74) *Attorney, Agent, or Firm* — Law Offices of Steven W. Weinrieb(57) **CLAIM**

The ornamental design for a jewelry organizer, as shown and described.

DESCRIPTION

FIG. 1 is a front, right side, top perspective view of a jewelry organizer showing my new design;

FIG. 2 is a rear right side, bottom perspective view thereof;

FIG. 3 is a front elevational view thereof;

FIG. 4 is a rear elevational view thereof;

FIG. 5 is a left side elevational view thereof; and,

FIG. 6 is a front, right side, top perspective view of the jewelry organizer showing the jewelry organizer being hung upon a clothes hanger.

The broken lines depict environmental that forms no part of the claimed design for the jewelry organizer.
